MOP

Conrad Fatland, Mount Prospect, Ill.

Application May 24, 1933, Serial No. 672,649

2 Claims. (Cl. 15—119)

This invention relates to mops, and the object of the invention is to provide a simple and efficient combined mop head and wringer, and one which allows the mop to be very conveniently removed from the head and replaced.

Of the accompanying drawing, Fig. 1 is an elevation of the mop, which embodies features of my invention; Fig. 2 is a sectional view thereof along the line 2—2 of Fig. 1; Fig. 3 is a sectional view along the line 3—3 of Fig. 1.

The mop head comprises a yoke, consisting of two curved bars 10 which are suitably fastened to any ordinary form of handle 11. The outer ends 19 of the bars provide bearings for the rollers 12 and 13. These rollers may be of any suitable material and may be journaled in the outer ends of the bars 10 in any suitable manner. In order to provide for suitably pressing the rollers together for wringing or operating purposes, I provide a second yoke 14 which has openings in its arms through which the spindles 16 of the roller 13 pass. These spindles also pass through slots 15 in the ends 19 of the yoke 10. Pins 17 are fixed to one of the yokes; in this case, the yoke 14; and these pins pass freely through openings in the bars 10; and springs 18 mounted on the pins continuously press the yoke 14 towards the roller 13. As a consequence of this arrangement, the roller 13 is continuously pressed towards the roller 12 and the mop 20 is pressed between the two rollers. The compression of the springs 18 and the size of the slots 15 are suitable for the purposes.

This application is a continuation in part of 35 the Patent No. 1,966,890, issued to me July 17, 1934.

To secure maximum results in expelling water from the mop 20, it is essential that normally the rollers 12 and 13 shall compress the mop to the 40 limit and that the arms 19 shall be prevented from being forced apart when the wringer is in use. Therefore, in order to conveniently insert the mop or remove it from between the rollers when so compressed, and in order to prevent said 45 arms from being forced apart, I provide an annular flange 23 on the outer end of each of the spindles 22 of the roller 12, and I form the openings 21 in the arms 19 large enough to allow said flanges to pass freely through and to permit lateral movement of said spindles 22. This arrangement makes both rollers movable longitudinally of the arms 19 sufficiently for the purposes, and when one end of the roller 12 is pressed inwardly, so that the flange 23 registers with the 55 opening 21, the arm 19 can be bent outwardly passing the spindle 22, of the roller 12, out of the opening 21, and the other end of the roller 12 can then be released by simply unhooking the 60 flanged spindle 22 from its bearing.

The operation is reversed when inserting the roller. The roller is inserted by first hooking one of the flanged spindles into its opening 21 in one of the arms 19, bending the opposite arm 19 outwardly and pressing that end of the roller 12 into place so as to let the flange 23 of the spindle 22 pass through the associated opening 21. 5

I claim as my invention:

1. A mop head wringer comprising a handle, a yoke-like pair of arms fixed to the handle, each arm having an outer and an inner opening adjacent its outer end, a pair of coating rollers journaled in the respective outer and inner openings, the inner openings being elongated, and the outer openings being materially larger than the associated spindles, both rollers being movable longitudinally of the arms in the openings, resilient means normally pressing the inner roller towards the outer roller, a flange on the outer end of each of the spindles of the outer roller, 20 each of said flanges having a lesser diameter than the diameter of its associated opening, said flanges being engaged to the outer surfaces of the associated arms when the outer roller is pressed outwardly by said resilient means to prevent the outward bending of the said arms in normal operation, one end of said outer roller being releasable by pressing it inwardly a distance slightly greater than the depth of the flange on its spindle and bending its associated arm outwardly, passing said spindle out of its bearing, and the other end of said roller then being releasable by unhooking its spindle from its bearing. 25 30

2. A mop head wringer comprising a handle, a yoke-like pair of arms fixed to the handle, each arm having an outer and an inner opening adjacent its outer end, a pair of coating rollers journaled in the respective outer and inner openings, the inner openings being elongated, the inner roller being movable longitudinally in the openings of its associated arms, resilient means normally pressing the inner roller towards the outer roller, one end of the outer roller being movable longitudinally in the opening of its associated arm, a flange on the outer end of the spindle of said outer roller end, said flange having a lesser diameter than the diameter of the associated opening, said flange being engaged to the outer surface of the associated arm when the outer roller is pressed outwardly by said resilient means to prevent the outward bending of the said arm in normal operation, said end of said outer roller being releasable by pressing it inwardly a distance slightly greater than the depth of the flange on its spindle and bending the associated arm outwardly and passing said spindle out of its bearing. 45 50 55 60
